SALT SHAKER WITH HANDLE

Clarence M. Burroughs, Glendale, Calif., assignor
to Burreoughs Manufacturing Corporation, Los
Angeles, Calif., a corporation of California

Application February 21, 1950, Serial No. 3,053

Term of patent 7 years

(Cl. D44—22)

To all whom it may concern:

Be it known that I, Clarence M. Burroughs, a citizen of the United States, residing at Glendale, in the county of Los Angeles and State of California, have invented a new, original, and ornamental Design for a Salt Shaker With Handle, of which the following is a specification, reference being had to the accompanying drawing, forming part thereof.

Figure 1 is a top plan view of a salt shaker with handle, showing my new design;

Figure 2 is a side elevational view;

Figure 3 is a front view;

Figure 4 is a rear view;

Figure 5 is a bottom view;

Figure 6 is a transverse section taken on the line 6—6 of Figure 1; and

Figure 7 is a fragmentary sectional view taken on the line 7—7 of Figure 2.

I claim:

The ornamental design for a salt shaker with handle, as shown.

CLARENCE M. BURROUGHS.
